United States Patent [19]

Gutkowski

US00D323293S

[11] Patent Number: Des. 323,293

[45] Date of Patent:  Jan. 21, 1992

[54] CONTAINER

[75] Inventor: Ronald R. Gutkowski, Racine, Wis.

[73] Assignee: S. C. Johnson & Son, Inc., Racine, Wis.

[] Term: 14 Years

[21] Appl. No.: 387,304

[22] Filed: Jul. 28, 1989

[52] U.S. Cl. D9/377; D9/373; D9/403

[58] Field of Search .... D9/377, 373, 403-413, D9/367, 435, 447, 449, 300; 215/1 R, 1 C; 222/212, 494
